INKING MECHANISM FOR PRINTING MACHINES

Application filed July 12, 1928. Serial No. 292,256.

The invention relates to inking mechanisms for printing machines, and more particularly to a mechanism in the ink fount for applying the ink to the ink fount roll in a manner to ensure a uniform and effective feeding of the ink by said roll to the ductor roll.

Printing machines of the planographic type are extensively used for impressing safety background tints upon paper used for various negotiable instruments, sensitive inks being commonly used in the production of such tints. The vehicles for such inks are so affected by the chemicals used to make them sensitive as to impart greater viscosity there- 15 to than characterizes ordinary litho varnish vehicle inks, and with a continued run of a press, the ink in the fount takes such form as to lose the intimate relation between same and the ink fount roll necessary to a proper 20 feeding of the ink to the ductor roll. Hence the quantity of ink delivered to said roll can not be controlled by the adjustable feed blade of the fount, but will be determined by the condition of the mass of ink in the fount 25 which is subject to constant variation.

With low speed presses, in order to permit the effective use of sensitive inks, it is necessary for the pressman to frequently work the ink with a hand spatula, but this does not 30 secure uniform and even feeding movement of the ink towards the ink fount roll nor a proper distribution of ink thereupon, except possibly immediately following each working of the ink. With high speed presses, the 35 ink fount or founts require almost constant attention to ensure proper inking when sensitive inks are being used.

To correct the above condition, it has been endeavored to use in the ink fount various 40 well known types of ink agitators, but when using sensitive inks, the ordinary agitators have been found not to give satisfactory results.

With the above conditions in mind, the invention contemplates an inking mechanism, in which the ink fount is provided with reciprocatory paddles so formed, and so actuated, as to force the ink in the fount upon a wide band of the peripheral area of the 50 ink fount roll prior to, and during, each actua-

tion of the roll so as to ensure a proper, continuous coating of the roll with ink throughout each actuation thereof.

In a printing machine equipped with the mechanism of the invention, the quantity of ink present in a fount is comparatively small as compared with the quantity of ink ordinarily used, and substantially the entire volume of ink is constantly brought and maintained in contact with, or in close proximity 55 to, the ink fount roll.

The manner of applying the ink to the ink fount roll permits the close setting of the feed blade of the fount and ensures a film of ink upon the portion of the roller engaged by the ductor roll with each transfer of ink thereto, of the desired thickness to ensure 60 the delivery of sufficient ink to the ductor roll.

The inking mechanism of the invention was 70 developed in connection with high speed, multicolor, offset, planographic printing machines, which have a plurality of plate cylinders and a plurality of ink founts associated with each cylinder. In connection 75 with a press of this character, the inking mechanism of the invention is particularly desirable, since during the run of the press, the ink founts require little or no attention from the pressman beyond an occasional inspection to ensure the maintenance of an adequate supply of ink in each fount.

Ordinarily, ink fount rollers receive rotary movement only during that interval when the ductor roll is in engagement therewith, 85 but it has been found desirable to so construct the inking mechanism that the ink will be applied to a portion of the roller while it is at rest, and also while it is being turned. The various paddles and their actuating 90 means are so constructed and so function as to force substantially the entire volume of ink in the fount, toward the ink fount roll, but to apply only a comparatively thin stratum of ink to the roll while at the same time effectively packing the space between the roll and the edge of the cutter plate with ink.

Since the paddles have reciprocatory movement and function in substantially the same manner, irrespective of the direction of this 95 100

movement, the mechanism is so constructed as to ensure the automatic adjustment of the position of the paddles to accord with the direction of their movement so as to ensure 5 the same action, so far as the application of ink to the roller is concerned, irrespective of the direction of movement of the paddles. The construction of the various paddles and their mode of operation, is such as to secure 10 this automatic adjustment of the various paddles as a result of resistance to their movement by the ink in the fount.

In an inking mechanism embodying the invention, it is desirable to so support the various 15 paddles and so connect them with their actuating means, as to permit of variation of the number of paddles and in the spacing of same within the fount, while at the same time avoiding projecting parts which might 20 interfere with free access to the press of the printing couple while the press is in operation.

The invention consists primarily in an inking mechanism for printing machines, embodying 25 therein in combination with an ink fount having a feed plate, an ink fount roll co-operating therewith, a ductor roll, and means for actuating said ink fount roll, of a reciprocatory member, means for actuating 30 same, a plurality of supports movable with said reciprocatory member, a paddle mounted upon and adapted to have free pivotal movement in relation to each of said supports, the lower edge of the paddle extending into 35 close proximity to said plate, and the free edge thereof extending into close proximity to said ink fount roll, and means limiting the movement of each paddle about its pivotal connection with the support; and in such other 40 novel features of construction and combination of parts, as are hereinafter set forth and described, and more particularly pointed out in the claims hereto appended.

Referring to the drawings,

45 Fig. 1 is a side view of an inking mechanism embodying the invention with a portion of the wall of the ink fount and a portion of the ink fount roll broken away to disclose the interior, and a portion of the paddle mechanism within, the fount;

Fig. 2 is a rear elevation at one end of the fount;

Fig. 3 is a plan view adjacent one end of the fount;

50 Fig. 4 is a detail view of one of the paddle mechanisms and its support, upon a larger scale; and

Fig. 5 is a plan view of Fig. 4.

Like numerals refer to like parts throughout the several views.

In the accompanying drawings, the invention is illustrated as embodied in a well known construction of ink fount, embodying therein the usual container 10 and its adjustable 65 feed plate 11. Mounted in the fount, adja-

cent the edge of said feed plate, is an ordinary ink fount roll 12 carrying a ratchet wheel 13 by which it is intermittently turned. Associated with the ink fount roll 12 is an ordinary ductor roll 14 having associated therewith a cutting roll 15. A fragmentary portion of one of the distributing rolls co-operating with the ductor roll 14 is shown at 16.

Mounted concentric with the ink fount roll 12 and its ratchet wheel 13, is a bell crank lever 17 carrying a pawl 18, co-operating with the ratchet wheel 13. One arm of this lever is connected by a link 19 with a bell crank lever 20 which is actuated from a crank wheel 21 upon the shaft of the distributing roller 16, by a link 22.

The foregoing mechanisms are old and well known in the art, and in their specific details form no part of the present invention which relates more particularly to the combination with such or a similar ink fount mechanism, of a particular construction of paddle mechanism which will now be described.

Mounted in suitable bearings 23 upon the ink fount 10 is a slidable bar 24 adapted to be reciprocated by means of a bell crank lever 25 mounted upon a fitting 26 carried by the ink fount frame. One arm of this lever 25 is connected to the bar 24 by means of a link 27, and the other arm is connected by a link 28 with one arm of the bell crank lever 20. This actuating means ensures movement of the paddles actuated thereby in one direction, while the pawl 18 is riding idly over the teeth of the ratchet wheel 13, and movement in the opposite direction, while said pawl is imparting movement to said ratchet wheel and to the ink fount roll 12.

Carried by the bar 24 is a plurality of supports each of which is constructed the same as every other and has associated therewith a paddle, the manner of associating each paddle with its support being the same. A description of but one of these elements will, therefore, be entered into.

Each of said supports consists of a bracket 29 having a yoke 30 adapted to straddle the slide bar 24 and be secured thereto by means of a set screw 31. This bracket is of cast metal and has secured thereto, by means of a clamp nut 32, a plate 33, the lower edge of which extends substantially parallel with the feed plate 11. Pivotedly mounted upon the plate 33, by means of a hinge 34, is a trapezium-shaped paddle 35, which, like the plate 33, is of sheet metal. The lower edge of this paddle extends into close proximity to the feed plate 11, and the substantially vertical edge thereof extends into close proximity to the ink fount roll 12 and tangentially to the periphery thereof.

The bracket 29 brings substantially the entire paddle mechanism within the confines of the ink fount so as to leave a clear field

above this fount to enable the pressman to reach over the fount and do any necessary work upon the impression cylinder of the printing couple while the press is in operation.

Furthermore, the yoke 30 and set screw 31 permit a plate 33 and its paddle 35 to be adjusted along and set at any point of, the slide bar 24, or to be brought into any desired relation to adjacent supports and paddles.

To secure the desired movement of the ink in the fount 10 toward and into engagement with the ink fount roll 12, it is essential that the paddle 35, while it is operative to so move the ink, shall be set at an angle to the plate 33, sheer in this paddle being necessary in order to crowd the ink toward the roll 12, but to cause a fairly thin stratum of ink to be applied to the ink fount roll 12, it is necessary to provide means defining the extreme angular relation of the paddle with the plate 33. Since the support 33 and the paddle 35 have movement in both directions, it is necessary to provide such means which will permit a limited turning movement of the paddle about its point of pivotal support, (the hinge 34) according to the direction of movement of the slide bar 24 and the support 33. This reversal in the position of the paddle, with a reversal of the movement of the bar 24, is essential in order to secure the desired mode of operation of the inking mechanism as a whole.

The means limiting the movement of the paddle about its pivotal connection consists of a member 36 straddling the paddle 35 and mounted upon the pin of the hinge 34, this member having divergent stop members 37 and 38 adapted respectively to engage the plate 33 according to the direction of movement of the paddle 35 and the bar 24.

The operation of the herein described mechanism is substantially as follows:—

With the parts in the position shown more particularly in Figs. 1 to 3, the ink fount roll 12 will be at rest and the ductor roll 14 will be disengaged therefrom and be engaged with the distributing roller 16 so as to transfer ink thereto. With the continued rotation of the crank wheel 21, however, the bell crank lever 20 will be so reciprocated as to oscillate the bell crank lever 17 and cause the pawl 18 to move to the left, Fig. 1, and ride over the teeth of the ratchet wheel 13 without imparting any movement to the ink fount roller. With this movement of the bell crank lever 20, however, the link 28 will oscillate the bell crank lever 25, and through the thrust of the link 27 upon the bar 24, move this bar carrying with it the various brackets 29 and plates 33 to the right, Fig. 3. During the first part of this movement of the plates 33, the various paddles 35 will have substantially no movement with relation to the ink fount roll 12, but since

they are free to turn about the hinge 34, the re-

sistance to their movement with the plate 33 offered by the ink, will cause such turning movement without movement of the paddle in relation to the roll 12.

The pivotal movement of the paddle will, however, bring one of the stop members as 37 into engagement with the side of the plate 33 and stop such turning movement of the paddle, with the paddle so positioned as to present an inclined surface to the ink. With the continued movement of the bar 24, the paddles will have movement therewith and thus crowd or force the ink in advance of each paddle toward the ink fount roll 12. By reason of the height of the paddle, this action will apply the ink to the roll 12 from the plate 11 to substantially the horizontal diameter of said roll. The stiffness or viscosity of the ink will assist in securing a desired application of the ink to the roll 12 by the various paddles, since the ink will have little or no tendency to flow between the vertical edge of the paddle and the roll, notwithstanding the suction back of the paddle. The travel of the various paddles 35 with the slide 24 will have a wiping action which will raise the level of the ink closely adjacent the ink fount roll 12 and apply a stratum of ink directly to the roll to the height above indicated.

Closely adjacent the feed plate 11, the ink will be forced toward the roller in sufficient volume to completely fill the space caused by the convergence of this plate and the perimeter of the roll 12. This movement of the paddles, while the ink roll 12 is at rest, assures an adequate supply of ink about the portion of the roller within the fount and adjacent the plate 11 preparatory to the initial turning movement of the roller incidental to the conveying of ink from the fount to a position where it can be picked up from the ink fount roll by the ductor roll 14. The raising of the level of the ink also ensures the application of the ink in a much wider band than that represented by the normal level of the ink in the fount.

When the crank wheel 21 has completed 180° of its movement necessary to impart the maximum movement to the bar 24 in one direction, there is a reversal of the movement of the various cranks and links and of the bar 24 together with the various paddles and their supports. During the early part of the movement in this reverse direction, the various paddles 35 will have no movement with the bar 24, but will merely have pivotal movement about the hinge 34 until the other stop 28 engages the plate 33, whereupon the proper angularity or sheer of the paddle will be established, and thereafter the paddles will have lineal movement with the bar 24 and will, as heretofore described, force or crowd the ink toward the roll during such lineal movement.

During the turning movement of the pad-

dles, the ink fount roll 12 will be having rotary movement and will be conducting ink in a thin stratum from the ink fount. The ink between the roll 12 and the plate 11 is 5 adequate to afford a sufficient supply of ink to ensure the continued application of ink to the roll during the turning movement of the paddles, but the sluggish character of the ink is such that following the initial movement 10 of the roll there will be a loss of that intimate contact between the roll and the main body of the ink necessary to maintain an adequate supply. This is due to the fact that the ink does not flow readily, even though the plate 15 11 is inclined. This characteristic is one which is peculiar to sensitive inks so far as this excessive sluggishness is concerned.

The lineal movement of the various paddles with the bar 24, however, ensures a continued 20 feeding of the ink toward the roll 12, and the wide band of ink applied thereto prior to the initial turning movement of the roll supplies ink to be carried with the roll toward the plate 11.

From the foregoing it will be clear that the 25 reciprocation of the paddles 35 in one direction, while the roll 12 is at rest, causes the application of ink thereto in a wide band so as to ensure an adequate supply of ink during 30 the initial turning movement of the roll, and that the movement of the paddles in the opposite direction ensures the maintenance of an adequate supply of ink in direct contact with the roll during the actual feeding of the ink 35 thereby.

While the lineal movement of the paddles has the effect of raising the level of the ink 40 adjacent the roll 12, the turning of this roll will have the effect of restoring the ink level in advance of each of the paddles.

The purpose of the herein described mechanism is to constantly feed the ink toward the ink fount roll so as to maintain an adequate supply upon the roll in order to ensure an effective action of the plate 11 in delivering a 45 proper quantity of ink by means of the roll 12 to the ductor roll 14. The working of the ink is no function of the paddles, since such is unnecessary with high grade inks such as sensitive litho inks.

In the form of the invention shown in the drawings, the ink fount roll actuating pawl 18 and the slide 24 are accurately timed in 50 their operative effect upon the ink fount roll 12 and the paddles 35, since both of these parts are simultaneously actuated from the rocking bell crank lever 20. The movements of this lever 20 are rapid, since the printing machine with which the invention is used is a high speed machine, the difficulties in properly feeding the ink to the ductor roll having 55 developed because of such high speed.

The plate 33 and the paddles 35, being 60 formed of sheet metal, have slight flexibility, although this is not essential. By using the

yoked supports 29, each of the paddle mechanisms may be removed from the fount, not only to permit the cleaning of the fount, but of the paddle mechanisms themselves. If desired, in order to avoid the necessity for re-setting the various paddle mechanisms in 70 relation to the slide 24, the supporting plates 33 may be disconnected from the brackets 29 respectively, the use of the slot and bolt for connecting said supports to said brackets permitting the removal of the supports in the manner above described. 75

It is not my invention to limit the invention to the precise details of construction and combination of parts shown in the drawings, 80 it being apparent that such may be varied without departing from the spirit and scope of the invention.

Having described the invention, what I 85 claim as new and desire to have protected by Letters Patent, is:—

1. An inking mechanism for printing machines, embodying therein in combination with an ink fount having a feed plate, an ink fount roll co-operating therewith, a ductor roll, and means for actuating said ink fount roll, of a reciprocatory member, means for actuating same, a plurality of supports movable with said reciprocatory member, a paddle mounted upon and adapted to have free pivotal movement in relation to each of said supports, the lower edge of the paddle extending into close proximity to said plate, and the free edge thereof extending into close proximity to said ink fount roll, and means limiting 90 the movement of each paddle about its pivotal connection with the support. 95

2. An inking mechanism for printing machines, embodying therein in combination with an ink fount having a feed plate, an ink fount roll co-operating therewith, a ductor roll, and means for intermittently actuating 100 said ink fount roll, of a reciprocatory member, means imparting movement to said reciprocatory member in one direction while said ink fount roll is at rest, and imparting movement thereto in the opposite direction while said ink fount roll is in motion, a plurality of supports movable with said reciprocatory member, a paddle pivotally connected with 105 each of said supports, the lower edge of the paddle extending into close proximity to said plate, and the free edge thereof extending into close proximity to said ink fount roll, and means limiting the movement of each paddle about its pivotal connection with the support. 110

3. An inking mechanism for printing machines, embodying therein in combination with an ink fount having a feed plate, an ink fount roll co-operating therewith, a ductor roll, and means for actuating said ink fount roll, of a reciprocatory member, means for actuating same, a plurality of supports, means 115 detachably and adjustably mounting said 120

supports upon said member, a paddle pivotally connected with each of said supports, the lower edge of the paddle extending into close proximity to said plate, and the free edge thereof extending into close proximity to said ink fount roll, and means limiting the movement of each paddle about its pivotal connection with the support.

4. An inking mechanism for printing machines, embodying therein in combination with an ink fount having a feed plate, an ink fount roll co-operating therewith, a doctor roll, and means for actuating said ink fount roll, of a reciprocatory member, means for actuating same, a plurality of brackets, each having a yoke adapted to straddle the reciprocatory member, means co-operating with said yoke and said member for adjustably and removably connecting the bracket thereto, a plate detachably connected with said bracket, a paddle pivotally connected with said plate, the lower edge of the paddle extending into close proximity to said feed plate, and the free edge thereof extending into close proximity to said ink fount roll, and means limiting the movement of each paddle about its pivotal connection with the support.

5. An inking mechanism for printing machines, embodying therein in combination with an ink fount having a feed plate, an ink fount roll co-operating therewith, a doctor roll, and means for intermittently actuating said ink fount roll, of a reciprocatory member, means imparting movement to said reciprocatory member in one direction while said ink fount roll is at rest, and imparting movement thereto in the opposite direction while said ink fount roll is in motion, a plurality of supports, means detachably and adjustably mounting said supports upon said member, a paddle pivotally connected with each of said supports, the lower edge of the paddle extending into close proximity to said plate, and the free edge thereof extending into close proximity to said ink fount roll, and means limiting the movement of each paddle about its pivotal connection with the support.

6. An inking mechanism for printing machines, embodying therein in combination with an ink fount having a feed plate, an ink fount roll co-operating therewith, a doctor roll, and means for intermittently actuating said ink fount roll, of a reciprocatory member, means imparting movement to said reciprocatory member in one direction while said ink fount roll is at rest, and imparting movement thereto in the opposite direction while said ink fount roll is in motion, a plurality of brackets, each having a yoke adapted to straddle the reciprocatory member, means co-operating with said yoke and said member for adjustably and removably connecting the bracket thereto, a plate detachably connected with said bracket, a paddle pivotally con-

nected with said plate, the lower edge of the paddle extending into close proximity to said feed plate, and the free edge thereof extending into close proximity to said ink fount roll, and means limiting the movement of each paddle about its pivotal connection with the support.

7. An inking mechanism for printing machines, embodying therein in combination with an ink fount having a feed plate, an ink fount roll co-operating therewith, a doctor roll, a ratchet wheel carried by said ink fount roll, a pawl co-operating therewith, and means for actuating said pawl, including an oscillatory support therefor, a bell crank lever, connections between said lever and said support, a crank wheel, and a link connecting said crank wheel with said bell crank lever, of a reciprocatory member, a second bell crank lever, connections between one arm of said second bell crank lever and said reciprocatory member, and between the other arm of said bell crank lever and said first named bell crank lever, whereby said reciprocatory member will receive movement in one direction during movement of said pawl in relation to said ratchet, and will receive movement in the other direction during movement of said ratchet by said pawl, a plurality of supports movable with said reciprocatory member, a paddle pivotally connected with each of said supports, the lower edge of the paddle extending into close proximity to said plate, and the free edge thereof extending into close proximity to said ink fount roll, and means limiting the movement of each paddle about its pivotal connection with the support.

8. An inking mechanism for printing machines, embodying therein in combination with an ink fount having a feed plate, an ink fount roll co-operating therewith, a doctor roll, a ratchet wheel carried by said ink fount roll, a pawl co-operating therewith, and means for actuating said pawl, including an oscillatory support therefor, a bell crank lever, connections between said lever and said support, a crank wheel, and a link connecting said crank wheel with said bell crank lever, of a reciprocatory member, a second bell crank lever, connections between one arm of said second bell crank lever and said reciprocatory member, and between the other arm of said bell crank lever and said first named bell crank lever, whereby said reciprocatory member will receive movement in one direction during movement of said pawl in relation to said ratchet, and will receive movement in the other direction during movement of said ratchet by said pawl, a plurality of brackets, each having a yoke adapted to straddle the reciprocatory member, means co-operating with said yoke and said member for adjustably and removably connecting the bracket thereto, a plate detachably connected with said bracket, a paddle pivotally de-

tachably connected with said bracket, a paddle pivotally connected with said plate, the lower edge of the paddle extending into close proximity to said feed plate, and the free edge thereof extending into close proximity to said ink fount roll, and means limiting the movement of each paddle about its pivotal connection with the support.

9. An inking mechanism for printing machines, embodying therein in combination with an ink fount having a feed plate, an ink fount roll co-operating therewith, a doctor roll, and means for actuating said ink fount roll, of a reciprocatory member, means for actuating same, a plurality of brackets, each having a yoke adapted to straddle the reciprocatory member, means co-operating with said yoke and said member for adjustably and removably connecting the bracket thereto, a plate detachably connected with said bracket, a paddle pivotally connected with said plate, the lower edge of the paddle extending into close proximity to said feed plate, and the free edge thereof extending into close proximity to said ink fount roll, and a member mounted at the point of pivotal connection between said paddle and said plate, said member straddling and engaging said paddle, and having divergent stop members adapted respectively to engage said plate, whereby movement of each paddle about its pivotal connection with the support is limited.

35 In witness whereof I have hereunto affixed
my signature this 28th day of June, 1928.

FRANK C. MARQUARDT.
